UNITED STATES PATENT OFFICE

129,969

DESIGN FOR A STRETCHABLE TEXTILE FABRIC

William J. Roche, New York, N. Y.

Application September 19, 1941, Serial No. 103,423

Term of patent 3½ years

To all whom it may concern:

Be it known that I, William J. Roche, a citizen of the United States of America, residing in New York city, county of New York, and State of New York, have invented a new, original, and ornamental Design for a Stretchable Textile Fabric, of which the following is a specification, reference being had to the accompanying drawings, forming part thereof.

Fig. 1 is a plan view of a stretchable textile fabric showing my new design.

Fig. 2 is a plan view as shown in Fig. 1, showing the fabric in stretched position.

The design unit is contained between the dot and dash lines, which unit is repeated in regular succession as indicated by the extensions beyond the unit boundaries.

I claim:

The ornamental design for a stretchable textile fabric, substantially as shown and described.

WILLIAM J. ROCHE.
